UNITED STATES PATENT OFFICE.

MIRIAM GROSS, OF MILWAUKEE, WISCONSIN.

DESIGN FOR A KNITTED FABRIC.

Application filed May 12, 1927. Serial No. 21,941. Term of patent 14 years.

To all whom it may concern:

Be it known that I, MIRIAM GROSS, a citizen of the United States, residing at Milwaukee, in the county of Milwaukee and State of Wisconsin, have invented a new, original, and ornamental Design for a Knitted Fabric, of which the following is a specification, reference being had to the accompanying drawing, forming part thereof.

The drawing is a plan view of a piece of fabric embodying the invention.

An important feature of the design resides in the raised blocks which stand out from the body portion of the fabric and are of a contrasting stitch thereto.

I claim:
The ornamental design for a knitted fabric as shown and described.

MIRIAM GROSS.
